Inventor:

George G. Place

by *Albert J. Schell*
Attorney

UNITED STATES PATENT OFFICE.

GEORGE G. PLACE, OF CHICAGO, ILLINOIS.

HOLDER FOR SMOKING PIPES.

Application filed September 19, 1924. Serial No. 738,581.

To all whom it may concern:

Be it known that I, GEORGE G. PLACE, citizen of the United States, residing at Chicago, in the county of Cook and State of

5 Illinois, have invented certain new and useful Improvements in a Holder for Smoking Pipes; and I do hereby declare the following to be a full, clear, and exact description of the invention, such as will enable others 10 skilled in the art to which it appertains to make and use the same.

My invention relates to holders for smoking pipes and in its general objects includes the providing of a simple, inexpensive and 15 portable pipe holder which will be equally suitable as a rest for the empty pipe when not in use and as a support for a filled pipe during interruptions in its use. Furthermore, my invention provides a smoking pipe 20 holder which will effectively hold the pipe with the bowl so nearly upright as to prevent a spilling of the tobacco out of the bowl; which will allow for considerable variations in the size and shape of the various 25 portions of the pipe and particularly in the form of the stem without permitting the pipe to tip over, and which will support the pipe so that the stem will drain into the bowl.

30 Viewed in some further aspects, my invention provides a smoking pipe holder which can be constructed cheaply and with substantially equal facility of a wide variety of materials, such as wood, molded compositions, or pressed sheet metal, and which can be used advantageously without requiring the user to bend any portions of the holder so as to have these conform to variations in the size or shape of either the bowl 35 or the stem of the pipe. It also provides pipe holders of this class which can readily afford additional room either in the displaying of advertising matter or for the mounting of auxiliaries, such as match holders or 40 cigarette holders. Still further and also 45 more detailed objects will appear from the following specification and from the accompanying drawings, in which—

Fig. 1 is a perspective view of a smoking 50 pipe holder embodying my invention, showing this in a form which can be made equally well of a variety of materials, either in a solid form or in a downwardly open hollow form.

55 Fig. 2 is an enlarged central longitudinal section through a smoking pipe holder of

the type of Fig. 1 when this holder is made of wood or of any solid composition, showing the holder as supporting a pipe having a somewhat curved stem. 60

Fig. 3 is a section similar to Fig. 2 but showing a holder having a longer trough particularly suited for use with a pipe having a straight stem, and showing such a pipe supported by the holder. 65

Fig. 4 is a section taken similar to the section of Fig. 2, showing a holder of the general type of Fig. 1 but formed from sheet metal. 70

Fig. 5 is a fragmentary vertical section taken transversely of Fig. 4 along the correspondingly numbered line of that figure. 75

Referring to the illustrated embodiments, these all relate to smoking pipe holders adapted to be set upon a table, desk or other substantial horizontal surface. For example Fig. 1 shows the holder in the form of a solid block 8 provided with an upwardly open and substantially cup-shaped socket 1 adapted to receive the lower portion of the 80 bowl 2 of a smoking pipe. Leading sideways from this cup-shaped socket 1 is a groove or trough 3 which slopes upwardly from the said socket and desirably terminates within the upper surface of the block. This trough 85 3 affords a socket for a portion of the stem 4 of the pipe which is adjacent to the bowl and, owing to its inclination, the trough holds the stem at an incline sloping upward from the bowl of the pipe. Consequently, 90 the stem of the supported pipe drains into the bowl of the pipe, which is highly desirable, particularly when the holder is set upon any objects which might be stained or marred by drippings from the pipe. 95

In practice, the inclination required in the trough for this purpose is relatively small, so that the bowl of the pipe is not tilted to an extent sufficient for spilling tobacco out of the pipe if the latter is filled. Consequently, 100 my holder is not only adapted for supporting the pipe when entirely out of use, but will serve equally well for supporting the lighted pipe during interruptions on the part of the smoker, as for example when the 105 user is telephoning.

Owing to the simplicity of the presented construction, it will be obvious that such a smoking pipe holder can be manufactured very cheaply and that considerable variations can be allowed in the size of the cup-shaped socket 1, the width and depth of 110

the trough 3 and the inclination of the latter. That is to say, a variation in the inclination of the trough is permissible so long as this trough is sufficiently inclined to feed the 5 drip from the stem into the bowl of the pipe but not sufficiently inclined to spill tobacco out of the bowl. So also, the cup-shaped socket 1 may be somewhat larger in diameter than the portion of the pipe bowl housed by 10 it while still causing the lateral wall portions of this holder part to engage the pipe bowl so as to limit a rocking of the pipe in either direction about the stem of the pipe.

Where the precise size and shape of the 15 pipe with which the holder is to be employed is known in advance, the holder can be constructed to fit the pipe more snugly, as shown for example in connection with the straight stemmed pipe of Fig. 3, although it will be 20 obvious that even this form could also be employed to good advantage with pipes differing considerably in the sizes and shapes of their bowls and stems. Moreover, since both the cup-shaped socket portion 1 and 25 the trough 3 open upwardly and flare upwardly, holders of this type can readily be made of any suitable molded or cast composition instead of having the said socket and trough formations cut into the top of an 30 originally flat surface as would be required when making the holder of wood.

However, I do not wish to be limited to holder constructions in which a solid block 35 affords the thickness needed to allow for 8 the required depth of the said socket formation and for holding the tip of the pipe stem clear of the table or disk on which the holder is set. Instead, this elevation of the upper surface of the holder might be provided 40 merely by the edge portions of the holder, thus permitting the entire holder to be formed out of sheet material by simple punch press operations. Two vertical sections of such a sheet metal type, which ob- 45 viously might conform also in its upper appearance to Fig. 1, are shown in Figs. 4 and 5. In this case, owing to the stiffening effect of the outer vertical flange 7 and of the 50 socket formations 5 and which are respectively entered by the bowl and the stem of

the pipe, the entire holder can be made of rather thin metal, thereby reducing its shipping weight as well as its cost.

Moreover, I do not wish to be limited to any particular proportions of the holders as 55 here disclosed, nor to the particular contour or general shape shown in Fig. 1. Neither do I wish to be limited to the use of such an article for the sole purpose of supporting a smoking pipe, since the balance of the upper 60 surface of the holder can obviously afford considerable space for displaying advertising matter, for resting cigars or cigarettes on the same, or for having a match box 65 holder mounted thereon.

So also, it will be obvious that regardless of the material employed for its construction, the holder of my invention can be made up in a variety of finishes, so as to match other articles of wood or metal or to contrast with the same. Hence I do not wish to be limited in this respect, nor do I wish to be limited to the details of the construction and arrangement above disclosed, it being obvious that many variations might be 70 made without departing either from the spirit of my invention or from the appended 75 claim.

I claim as my invention:

A holder for smoking pipes including a 80 member formed to seat flat on a supporting surface and having its upper face provided with a cup-like socket and a trough leading at its inner end from the socket and merging at its outer end into the upper face of the 85 member, the trough being inclined throughout its length and formed to receive the pipe stem and the bottom of the socket being disposed in the plane of the bottom of the trough and formed to engage the bottom of the 90 pipe bowl whereby to firmly support the stem and bowl and with the pipe at a relatively slight angle to the plane of the member, the walls defining the socket being of such depth so as to engage and hold the 95 pipe bowl from rocking.

Signed at Chicago, Illinois, September 12, 1924.

GEORGE G. PLACE.
